Daniel M. Scypes & Samuel Smith, of Springville, Penn.
Assignors to
Smith, Francis and Wells, of same place,
Letters Patent No. 92, dated July 23. 1861.

Whole No. 1457-

The schedule referred to in these Letters Patent and making part of the same.

To all whom it may concern:

Be it known that we, D. M. Scypes and Samuel Smith, both of Springville, County of Chester, State of Pennsylvania, have invented or produced a new and original design for the plates of a Summer range, and we do hereby declare the accompanying drawings with the following explanation of the same to form a full, clear and exact description of the said design.

The drawing represents a front view of the range with its two oven doors.

The plate A which is secured to the brickwork or masonry has straight sides and bottom the upper edge being slightly arched, the upper corners being rounded and the whole being edged with a plain moulding within which is a scrolled and fo-

liated ornament inclosing a space containing a figure, that of one door representing a cook carrying a boar's head on a dish which is ornamented with sprigs and leaves, a knife and a sharpening steel being attached to a belt, which surrounds the waist of the figure. The figure on the other door is that of a female in the act of carving a fowl.

We claim the ornamental figures and forms represented in and by the accompanying drawing and forming together an ornamental design for a summer range.

In testimony whereof we have signed our names to this specification in the presence of two subscribing witnesses.
